UNITED STATES PATENT OFFICE.

JAMES A. WATSON, OF WASHINGTON, DISTRICT OF COLUMBIA, ASSIGNOR OF ONE-HALF TO RALPH W. LEE, OF SAME PLACE.

DESIGN FOR A CASING OR CAP FOR SPRAYING-NOZZLES.

SPECIFICATION forming part of Design No. 32,498, dated April 10, 1900.

Application filed December 11, 1899. Serial No. 740,012. Term of patent 7 years.

To all whom it may concern:

Be it known that I, JAMES A. WATSON, a citizen of the United States, residing at Washington, in the District of Columbia, have invented and produced a new and original Design for a Cap or Casing for Spraying-Nozzles, of which the following is a specification.

In the accompanying drawings, forming a part of this specification, Figure 1 is a plan view of a cap or casing, showing my new design. Fig. 2 is a side elevation, and Fig. 3 is a central sectional view.

As shown in the drawings, my design consists of a hollow body having a cylindrical wall 1, extending from the bottom nearly to the top thereof, a flat top 2 in a plane at right angles to the axis of the cylindrical wall 1, and a ring-like portion 3, joining the cylind-

rical wall 1 and the flat top 2. Said portion 3 is of greater diameter than the cylindrical portion, and in section, as shown in Fig. 3, it forms a reverse curve, joining said cylindrical wall and said top. Centrally arranged in the flat top is a circular opening 4.

Having described my invention, what I claim as new, and desire to secure by Letters Patent, is—

The design for a casing or cap for spraying-nozzles, as herein shown and described.

In testimony whereof I affix my signature in presence of two witnesses.

JAMES A. WATSON.

Witnesses:

GEO. W. STICKNEY,
GEO. E. TERRY.
